GAS BURNER

Garnet W. McKee, Rockford, Ill.

Application September 28, 1937, Serial No. 164,611

8 Claims. (Cl. 158—119)

The present invention relates generally to gas burners for furnaces and other heating apparatus. More particularly the invention relates to that type of gas burner which is known as an atmospheric burner and comprises as the main parts thereof a burned head; a Venturi type injecting tube which is connected at its large or discharge end to the burner head and is adapted to have air flow into its other or throated end; a nozzle which is connected by a pipe to receive gas under pressure and is adapted to jet the gas through the tube to the burner and cause it to entrain and draw into the tube from the atmosphere around the throated end of the tube a certain quantity of air; a valve which is connected to the gas supply pipe and is adapted to control the flow of gas to the nozzle; a thermostatically controlled motor and gear mechanism for automatically opening and closing the gas valve in response to temperature changes in the space in which the thermostat is located; and an air valve which is associated with the throated end of the injecting tube and is controlled automatically so that when the burner is shut off it is closed slightly before shift of the gas valve into its closed position in order to shut off the flow of air into the tube prior to stoppage of the gas from the nozzle and thus prevent the formation of a combustible mixture in the tube and resultant back-firing.

One object of the invention is to provide an atmospheric burner of this type which is an improvement upon, and is more efficient than, the burner which is disclosed in and forms the subject matter of United States Letters Patent No. 1,937,974, granted to me December 5, 1933.

Another object of the invention is to provide an atmospheric gas burner of the aforementioned type in which the air valve, that is, the valve for controlling the flow of air into the throated end of the injecting tube is of the rotary register type and is controlled automatically by way of a solenoid in circuit with the motor of the thermostatically controlled mechanism for automatically opening and closing the gas valve.

Other objects of the invention and the various advantages and characteristics of the present gas burner will be apparent from a consideration of the following detailed description.

The invention consists in the several novel features which are hereinafter set forth and are more particularly defined by claims at the conclusion hereof.

In the drawings which accompany and form

a part of this specification or disclosure and in which like numerals of reference denote corresponding parts throughout the several views:

Figure 1 is a perspective of a gas burner embodying the invention;

Figure 2 is a perspective of the thermostatically controlled motor and gear mechanism for automatically opening and closing the gas valve;

Figure 3 is a vertical longitudinal sectional view of the motor and gear mechanism;

Figure 4 is a vertical transverse sectional view taken on the line 4—4 of Figure 3;

Figure 5 is a vertical longitudinal sectional view of the burner head and injecting tube illustrating in detail the design and construction of the air valve for controlling the flow of air into the throated end of the tube; and

Figure 6 is a diagrammatic view of the electrical circuit for the motor of the gas valve controlling mechanism and the solenoid for actuating or shifting the air valve.

The burner which is shown in the drawings constitutes the preferred embodiment of the invention and is essentially a gas burner of the atmospheric type. It is adapted for use in connection with a furnace or heating apparatus having a combustion chamber defining wall *w* and comprises a burner head *1*, a Venturi type injecting tube *8*, and a nozzle *9*.

The burner head *1* is in the form of a sleeve *30* and is adapted to receive a mixture of gas and air from the injecting tube *8*. It is adapted to fit against the inner face of the wall *w* of the heating apparatus as shown in Figure 1, and embodies an internal outwardly tapered annular flange *10*. The latter is adapted to increase the velocity of the fuel mixture as it emanates from the burner head and has an annular series of holes or apertures *11* which extend from the inner face of the flange to the outer face and cause a portion of the fuel mixture to flow outwards in the form of an annular series of jets around the main portion of the mixture. An externally threaded pipe nipple *12* serves to connect the burner head to the discharge end of the injecting tube *8*. One end of this nipple fits within an internally threaded socket *13* in the inlet end of the burner head and the other end of the tube fits in an internally threaded socket *14* in the discharge end of the tube. The tube *8*, as shown in Figure 5, flares from the inlet end thereof to the outlet with the result that it has a throat *15* at its inlet end. In addition to the throat *15* the tube has a mixing sleeve *16*. This sleeve forms a part of the throated

end of the tube and is connected at one end thereof to an annular flange 17 on the inlet end of the tube 8 by a screw thread connection 18. The other end of the mixing sleeve 16 has a cross-wall 19 with an annular series of spaced radially extending slots 20 therein and is adapted when the burner is in operation to have air drawn into it through the slots 20.

The nozzle 9 is centrally positioned in the mixing sleeve 16 and is adapted to receive gas under pressure from any suitable source of supply by way of a hollow member 21 and a pipe 22. The hollow element 21 is disposed in and formed integrally with the mixing sleeve 16 and communicates with a gas inlet branch 23 which projects radially from and is also formed integrally with the sleeve. The pipe 22 serves to supply gas to the member 21 for delivery to the nozzle 9. It is controlled by a valve 24 and includes a pipe section 25, an elbow 26, and a pipe connection 27. The valve serves to control the flow of gas through the pipe 22 to the nozzle and embodies a casing 28 and a valve member 29. The casing 28 is provided with a gas inlet 30 and an outlet 31 and has a cross-wall 32 which serves to separate the inlet from the outlet. As shown in Figure 3 the cross wall embodies a horizontally extending part 33 with a vertically extending aperture 34 therethrough. The valve member embodies an upstanding stem 35 and is vertically shiftable, as hereinafter described, to open and close the valve. The stem 35 extends through an opening 36 in the top portion of the valve casing 28 and is surrounded by a diaphragm 37. The latter extends between the stem and the portion of the casing which defines the opening 36 and prevents the escape of gas via said opening. The pipe section 25 extends horizontally and is connected at one end thereof to the outlet 31 of the valve casing 28. The other end of the pipe section 25 is connected to one branch or end of the elbow 26. The other branch of the elbow extends vertically and communicates with the inlet branch 23 of the mixing sleeve 16 by way of the pipe section 27. The injecting tube is supported at its throated end by the gas pipe 22 and is supported at its discharge or outlet end by the pipe nipple 12 which, as shown in Figure 1, extends through a hole 38 in the combustion chamber forming wall w of the heating apparatus with which the burner is associated. The nozzle 9 is located in the mixing sleeve 16 and faces towards the burner head 7. When the valve 24 is open, gas under pressure flows through the valve casing 28, the pipe section 25, the elbow 26, and the pipe section 27 to the gas inlet branch 23 of the mixing sleeve 16. From this inlet branch the gas flows upwards into the hollow member 21 and then is directed in jet form longitudinally through the injecting tube 8 to the burner head 7. As the gas flows from the mixing sleeve 16 into the throat 15 of the tube it entrains air from the atmosphere surrounding the sleeve. Such air flows inwards through the slots 20 in the cross-wall 19 of the mixing sleeve and mixes with the gas as the latter passes through the injecting tube and hence forms a fuel mixture prior to passage to the burner head 7. As soon as the fuel mixture passes through the annular flange 10 and the holes or apertures 11 in the flange it unites with additional air in the combustion chamber of the heating apparatus and burns. A needle valve 39 extends horizontally through the upper portion of the hollow member 21 in the mixing sleeve 16 and serves to control the jetting of gas through

the nozzle 9. This needle valve embodies a point at one end thereof which fits within the inner end of the nozzle 9. The other end of the needle valve is externally threaded and fits within an internally threaded hollow stem 40 at the back portion of the hollow element 21. The stem 40, as shown in Figure 1, extends through the central portion of the cross-wall 19 of the mixing sleeve 16. The rear or threaded end of the sleeve valve embodies a kerf 41 whereby it may be turned with a screw driver or other turning tool for adjustment purposes.

In addition to the burner head 7, the injecting tube 8, and the nozzle 9, the burner comprises a motor and gear mechanism 42 for opening and closing the gas valve 24, a thermostat 43 for controlling the gas valve automatically in response to temperature changes, a valve 44 for controlling the flow of air into the throttled end of the injecting tube 8, and a solenoid 45 for actuating or shifting the air valve.

The mechanism 42 is mounted on and positioned above the casing 28 of the valve 24 and comprises a frame 46, an electric motor 47, and speed reducing gearing between the motor and the stem 35 of the valve member 29. The frame comprises a base plate 48, a pair of upstanding sides 49 and 50, and a sheet metal housing 51. The base plate 48 is rectangular and embodies at the under side thereof a depending annular flange 52. The latter corresponds in shape to the portion of the valve casing which defines the opening 36 and serves to hold the marginal portion of the diaphragm 37 in clamped relation with said portion of the casing. The central portion of the base plate 48 has an aperture or hole through which the upper end of the stem 35 projects. The sides 49 and 50 rest upon the side margins of the base plate 48 and are secured in laterally spaced relation by spacers 53. The housing 51 surrounds the frame sides and serves as a closure or protective medium for the motor 47 and the speed reducing gearing between the motor and the stem 35. The electric motor 47 is disposed between the frame sides 49 and 50 and comprises an armature 54 and field coils 55 around the armature. The armature extends transversely of the frame and embodies a shaft 56 which is journaled in bearings on the sides 49 and 50 of the frame 46. The speed reducing gearing between the motor and the stem 35 comprises a pinion 57 on one end of the armature shaft, a gear 58 in mesh with the pinion 57 and on a transversely extending shaft 59, a pinion 60 on the shaft 59, a gear 61 in mesh with the pinion 60 and on a shaft 62, and a pinion 63 on the shaft 62 and in mesh with a rack 35a on the upper end of the stem 35 of the valve member 29. The shafts 59 and 62 extend transversely of the frame 46 of the motor and gear mechanism 42 and are journaled in bearings on the frame sides 49 and 50. When current is supplied to the motor 47 the armature shaft 54 operates through the medium of the speed reducing gearing between it and the stem 35 to raise the valve member 29 into its open position. A coil spring 64 is mounted on the shaft 62 and serves when current to the motor 47 is cut off to drive the speed reducing gearing in the reverse direction so as to lower the valve member 29 into its closed position. This spring is connected at one end thereof to the frame side 50 and at its other end to the shaft 62 and is adapted to be wound or placed under tension when the shaft 62 is rotated by the motor 47 in order to open the valve. The electric motor 47

47 is supplied with current by way of a pair of line conductors 65 and 66 and is subject to control by the thermostat 43 and a limit switch 67. The thermostat 43 is located in, or subject to the temperature of, the space to be heated by the burner and is in the form of a switch. It is associated with the line conductor 65 and comprises a bimetallic element 68 and a pair of contacts 69 and 70. The contact 69 is connected to one end 5 of the bimetallic element 68 and is adapted in response to lowering of the temperature in the space to be heated to be swung by the element 68 into contact with the contact 70 and to close the conductor 65 and thus complete the motor circuit. When the temperature in the space rises to a predetermined point the bimetallic element 68 is adapted to swing or move so as to disengage the contact 69 from the contact 70 and thus open the conductor 65 and the motor circuit. When 10 the thermostat is closed current is supplied to the motor 47 and the latter through the medium of the speed reducing gearing opens the valve member 49 and thus causes gas to flow to the nozzle 9 to start the burner. The limit switch 67 is included in the line conductor 68 between the thermostat 43 and the motor 47 and operates to break the motor circuit when the valve member 29 is raised by the motor into its fully opened position. It is controlled by a pin 71 and comprises 15 a pair of contacts 72 and 73 and a flexible element 74. The contact 72 is mounted on the element 74 and is normally held by said element in contact or engagement with the contact 73. When the contacts 69 and 70 of the thermostat 43 are 20 engaged with one another and the contacts 72 and 73 of the limit switch 67 are in contact current flows through the motor 47 and the latter, as hereinbefore described, operates through the medium of speed reducing gearing of the mechanism 42 to open the valve 24. The limit switch, as shown in Figure 2, is mounted on a panel 75 on the side 49 of the frame 46. The pin 71 is formed of any suitable insulating material and is carried by and radiates from a collar 76 which 25 is disposed adjacent to the panel 75 and is fixed to one end of the shaft 62. Said pin 71 rotates with the shaft 62 and is so arranged that when the valve member 29 of the valve 24 approaches or reaches its fully opened position it strikes 30 against the flexible element 74 and forces the latter in such manner as to disengage the contact 72 from the contact 73 and thus open the limit switch 67. As soon as this switch is opened the circuit for the motor is broken and the motor 35 hence stops. In order to hold the valve member 29 in its raised or open position after opening of the limit switch 69 and while the thermostat 43 is in its closed position an electromagnet 77 and an armature 78 are provided. The magnet and 40 armature are located between the sides 49 and 50 of the frame 46 and are positioned in opposed relation with the motor 47. The armature 78 is pivotally supported on a shaft 79 and is adapted to swing towards the core piece of the electro- 45 magnet when the magnet is energized and to be swung away from said core piece by a spring 80 when the magnet is deenergized. A dog 81 is connected to the distal end of the armature 78 and is adapted when the armature is swung toward the magnet as the result of the latter being energized to swing into engagement with the gear 58 and lock the latter together with the other parts of the speed reducing gearing against rotation. The magnet 77 is supplied with current 50 from the line conductors by way of a pair of conductors 82 and 83 and is controlled by a switch 84 on the panel 75 so that it is automatically energized when the limit switch 67 is broken. The switch 84 comprises a pair of contacts 85 and 86 and is disposed between the flexible element 74 and one end of the conductor 82. The other end of the conductor is connected to one end of the coil of the magnet. The conductor 83 leads from the other end of the magnet coil to the line conductor 66. The contact 85 is mounted on the element 74 and is adapted when the element is flexed by the pin 71 so as to break or open the switch 67 to be swung by the element 74 into engagement with the contact 86 and thus close the circuit through the electromagnet 77. When the magnet is energized as the result of closing of the switch 84 the armature 78 is swung towards the core piece of the magnet and brings the dog 81 into locked relation with the gear 58. When the thermostat 43 opens the contacts 69 and 70 as the 10 result of the temperature of the space to be heated reaching the proper point or degree the line conductor 65 is broken and as a result the flow of current through the electromagnet 77 ceases. As soon as the magnet becomes deenergized the armature 78 swings from the pole piece of the magnet as the result of the action of the spring 80 and releases the dog 81 from the gear 58. Upon release of the dog the coil spring 64 rotates the speed reducing gearing so 15 as to lower the valve member 29 to its closed position. During reverse rotation of the gearing the pin 71 swings away from the flexible element 74 and the latter is permitted to swing back to its normal position wherein it serves to close the limit switch 67 and maintains the switch 84 open. As a result of the action of the electric motor 47 and the electromagnet 77 with their respective control switches (67, 84) the valve 24 is opened 20 when the thermostat 43 closes and remains open 25 as long as the thermostat is closed. Upon opening of the thermostat as the result of a rise in temperature of the space to be heated, the gear 62 is released as a result of the magnet becoming deenergized and the valve member 29 is lowered automatically into its closed position by the action of the coil spring 64. Because of the speed reducing gearing between the electric motor 47 and the stem 35 of the valve member 29 the valve 30 opens and closes slowly. 35

The valve 44 for controlling the flow of air into the mixing sleeve 16 of the injecting tube is of the rotary register type and is controlled, as hereinafter described, so that it is opened when the thermostat 43 is closed and is closed slightly 40 before the valve 24 upon opening of the thermostat. By controlling the air valve 44 so that it closes before the gas valve, air cannot flow into the mixing sleeve 16 and dilute the gas and air mixture in the injecting tube to the point 45 where it becomes a combustible mixture and ignites with explosive violence. The small amount of gas which flows into the injecting tube after closing of the air valve 44 and the gas valve 28 so enriches the gas and air mixture that such 50 mixture becomes non-explosive and hence the flame at the end of the burner head 7 dies out gradually and without any back firing within the tube. The valve 44 fits against the cross-wall 55 19 of the mixing sleeve 16 and has a centrally disposed hub 87. The latter, as shown in Figure 5, is mounted on the outer end of the hollow stem 40 and permits the valve to rotate. The portion 60 of the valve 44 which fits against the cross-wall 65 is provided with an annular series of laterally 65 disposed 70

spaced slots 88. These slots are adapted in response to rotation of the valve to be brought into and out of registry with the slots 20 of the cross-wall. When the valve 44 is rotated so that the slots 88 thereof are in registry with the slots 20 of the cross-wall the valve is in its open position and air is permitted to flow into the mixing sleeve 16 for mixture with the gas. When the valve is rotated so as to bring the slots 88 thereof out of registry with the slots 20 the valve becomes closed and precludes inflow of air into the mixing sleeve.

The solenoid 45 constitutes the actuating medium for the air valve 44 and comprises a coil 89. The latter is located a small distance outwards and beneath the mixing sleeve 16 and is mounted on a base plate 90 which is fixedly secured by way of a screw 91 to a laterally extending lug 92 on the central portion of the elbow 26. The coil is suitably mounted between inner and outer concentrically arranged walls and has an armature 93 associated therewith. This armature is mounted for vertical sliding movement in the coil 89 of the solenoid and is connected at its upper end by a link 94 to a stud 95 on the register type air valve 44. The stud is fixed to and projects outwardly from the valve 44 and constitutes a crank. The link 94 extends between and is pivotally connected to the outer end of the crank forming stud 95 and the upper end of the armature 93. The armature is adapted when the solenoid is energized to slide upwards and operates through the medium of the link 94 and the stud 95 to rotate the valve 44 into its open position. When the solenoid is deenergized the armature is adapted to slide downwards in response to the action of gravity and effects closing of the air valve. The coil 89 of the solenoid is adapted to be energized upon closing of the thermostat 43 and is connected to receive current from the line conductors 65 and 66 by a pair of conductors 96 and 97. The conductor 96 is connected to one end of the coil 89 of the solenoid and is attached at its other end to the line conductor 65 at a point between the contact 70 of the thermostat 43 and the flexible element 74 of the limit switch 67. The other conductor, that is the conductor 97, extends between and is connected to the line conductor 66 and the other end of the coil 89. When the thermostat 43 is closed for burner operating purposes, current flows through the conductor 96, the coil 89, the conductor 97, and the line conductor 66 and hence the solenoid becomes energized and effects opening of the air valve 44 through the medium of the armature 93, the link 94, and the stud 95. When the thermostat 43 opens, the circuit through the solenoid is broken and the solenoid becomes deenergized with the result that the armature 93 slides downward in response to the action of gravity as hereinbefore pointed out, and effects closing of the valve 44. By reason of the fact that the armature 93 slides downwards in response to the action of gravity as soon as the solenoid 45 becomes deenergized there is a substantially instantaneous closing of the air valve 44 upon opening of the thermostat 43. Since upon opening of the thermostat there is a substantially instantaneous closing of the air valve and a slow closing of the gas valve, the burner is not likely to back-fire due to an over supply of air in the injecting tube.

Assuming that there is a pilot light or other starting means at the inner end of the burner head 1, the operation of the burner is as follows:

When the space to be heated is at the proper temperature and the thermostat 43 is in its open position the line conductor 65 is thus broken against the passage of current therethrough. When the temperature of the space drops so that it is necessary to bring the burner into play the thermostat closes and thus completes or closes the line conductor 65. Upon closing of the thermostat the following circuit is set up through the solenoid 45: thermostat 43; line conductor 65; conductor 95; coil 89; conductor 97; and line conductor 66. Upon completion of this circuit the solenoid is energized and results in immediate opening of the air valve 44. Simultaneously with the completion of the aforementioned circuit the following circuit is set up through the motor 47 of the gas valve controlling mechanism 42: thermostat 43; line conductor 65; flexible element 74; contacts 72 and 73 of limit switch 67; motor 47; and line conductor 66. As soon as this circuit is completed the electric motor 47 operates to drive the speed reducing gearing between it and the stem 35 of the valve member 29 and effects opening of the valve. As soon as the valve member 29 approaches or reaches its fully opened position the pin 71 on the collar 75 swings into engagement with the flexible element 74 and breaks the aforementioned circuit and establishes the following circuit through the electromagnet 77: thermostat 43; line conductor 65; flexible element 74; contacts 85 and 86 of switch 84; electromagnet 77; conductor 83; and line conductor 66. Upon completion of this circuit the armature 78 is swung towards the core piece of the magnet 77 and brings the dog 81 into locked relation with the gear 58 so as to hold the valve member against closing as a result of the action of the coil spring 64. As long as the thermostat 43 remains closed the gas valve 24 and the air valve 44 are held in their open position. As soon as the gas valve is opened gas flows through the nozzle 9 and passes in jet form through the tube 15. As the gas flows through the tube in jet form it entrains air from the atmosphere surrounding the mixing sleeve 16 and unites with the entrained air to form a fuel mixture which burns as it passes from the burner head 1. By reason of the fact that when the thermostat closes the air valve opens instantaneously whereas the gas valve 24, opens slowly the valve 44 is in its open position when the gas passing through the pipe 22 reaches the nozzle 9. When the thermostat opens as a result of the space to be heated reaching its proper or predetermined temperature the circuit through the solenoid and the circuit through the electromagnet both become broken. As soon as the flow of current through the solenoid ceases the valve 44 is swung into its closed position, as hereinbefore pointed out, and cuts off any additional inflow of air into the mixing sleeve 16. As soon as the circuit through the electromagnet 77 is broken the armature 78 swings away from the core piece of the magnet 77 as the result of the action of the spring 80 and causes the dog 81 to move out of engagement with the gear 58. Upon release of the dog the spring 64 operates to close the valve member 29 and thus effects stoppage of the flow of gas through the pipe 22 to the nozzle 9. As soon as the flow of gas stops the action of the burner ceases.

The herein described gas burner consists of but a small number of parts and hence may be manufactured at a low and reasonable cost. It is especially efficient in operation due to the fact

that backfiring is effectively prevented as the result of instantaneous closing of the air valve 44 and gradual closing of the gas valve 24.

Whereas the burner has been described as comprising but a single injecting tube 8 it is to be understood that a battery or series of injecting tubes may be employed with individual solenoid controlled air valves and but a single mechanism 42 for controlling the flow of gas. It is also to be understood that the invention is not to be restricted to any specific type of injecting tube or nozzle or to any of the specific details set forth, since these may be modified within the scope of the appended claims 15 without departing from the spirit and scope of the invention.

Having thus described the invention, what I claim as new and desire to secure by Letters Patent is:

20 1. A burner of the character described comprising in combination an injecting tube having a burner head at one end thereof and adapted to have air flow into its other end, a nozzle connected to receive gas under pressure and arranged to direct the gas so that it flows in jet form through the tube to the burner head and entrains air into said other end of the tube for mixture therewith, a valve for controlling the supply of gas to the nozzle, a valve for controlling the flow of air into said other end of the tube, a switch controlled source of electric current, mechanism, including a source supplied electric motor and adapted upon closing of the switch slowly to open the gas valve and upon 25 opening of such switch slowly to close said gas valve, and electric means independent of said mechanism connected to receive current from said source and adapted upon closing of the switch substantially instantaneously to open the air valve and upon opening of said switch substantially instantaneously to close the air valve.

2. An atmospheric burner of the character described comprising in combination a Venturi type injecting tube having a burner head at its large end and adapted to have air flow into its throated end, a nozzle connected to receive gas under pressure and arranged to direct the gas so that it flows in jet form through the tube of the burner head and entrains air into the throated end of the tube for mixture therewith, a valve for controlling the supply of gas to the nozzle, a valve for controlling the flow of air into the throated end of the tube, a switch controlled source of electric current, mechanism for controlling the gas valve including an electric motor connected to said source and speed reducing gearing between the motor and the gas valve, and adapted upon closing of the switch slowly to open the gas valve and upon opening of the switch slowly to close the valve, and an electrical device independent of said mechanism, connected to receive current from said source, and adapted upon closing of the switch substantially instantaneously to open the air valve and upon opening of said switch substantially instantaneously to close the air valve.

3. A burner of the character described comprising in combination an injecting tube having a burner head at one end thereof and adapted to have air flow into its other end, a nozzle connected to receive gas under pressure and arranged to direct the gas so that it flows in jet form through the tube to the burner head and entrains air into said other end of the tube for mixture therewith, a valve for controlling

the supply of gas to the nozzle, a valve for controlling the flow of air into said other end of the tube, a switch controlled source of electric current, mechanism for controlling the gas valve including a source supplied electric motor and adapted upon shift of the switch into one of its positions slowly to open the gas valve and upon shift of the switch into its other position slowly to close said gas valve, and means including a solenoid in the same circuit as the electric motor, and adapted upon closing of the switch substantially instantaneously to open the air valve and upon opening of the switch substantially instantaneously to close the air valve.

4. An atmospheric burner of the character described comprising in combination a Venturi type injecting tube having a burner head at its large end and adapted to have air flow into its throated end, a nozzle connected to receive gas under pressure and arranged to direct the gas so that it flows in jet form through the tube to the burner head and entrains air into the throated end of the tube for mixture therewith, a valve for controlling the supply of gas to the nozzle, a valve for controlling the flow of air into the throated end of the tube, a switch controlled source of current supply, gear type mechanism for shifting the gas valve including an electric motor connected to said source and adapted upon closing of the switch slowly to open said gas valve, and also including spring means adapted upon opening of the switch slowly to close the gas valve, and means including a source supplied solenoid and adapted upon closing of said switch to have the solenoid thereof energized and substantially instantaneously to open the air valve and also upon opening of said switch to have said solenoid deenergized and substantially instantaneously to close said air valve.

5. A burner of the character described comprising in combination an injecting tube having a burner head at one end thereof and adapted to have air flow into its other end, a nozzle connected to receive gas under pressure and arranged to direct the gas so that it flows in jet form through the tube to the burner head and entrains air into said other end of the tube for mixture therewith, a valve for controlling the supply of gas to the nozzle, a valve for controlling the flow of air into said other end of the tube, a motorized mechanism for slowly opening and closing the gas valve, and automatic means including a solenoid in the same circuit as the motor of said mechanism and adapted upon starting of the mechanism to open the gas valve substantially instantaneously to open the air valve, and upon starting of the mechanism to close the gas valve substantially instantaneously to close said air valve.

6. A burner of the character described comprising in combination an injecting tube having a burner head at one end thereof and adapted to have air flow into its other end, a nozzle connected to receive gas under pressure and arranged to direct the gas so that it flows in jet form through the tube to the burner head and entrains air into said other end of the tube for mixture therewith, a valve for controlling the supply of gas to the nozzle, a valve for controlling the flow of air into said other end of the tube, a thermostatically controlled mechanism for slowly opening the gas valve when the temperature of the space heated by the burner drops to a predetermined point and for slowly opening the gas valve when the temperature of said space rises to a predetermined

point, and automatic electric means independent of said mechanism adapted substantially instantaneously to open the air valve when the mechanism starts to open the gas valve and substantially 5 instantaneously to close said air valve when the mechanism starts to close said gas valve.

7. An atmospheric burner of the character described comprising in combination a Venturi type injecting tube having a burner head at its 10 large end and adapted to have air flow into its throated end, a nozzle connected to receive gas under pressure and arranged to direct the gas so that it flows in jet form through the tube to the burner head and entrains air into the throated 15 end of the tube for mixture therewith, a valve for controlling the supply of gas to the nozzle, a valve for controlling the flow of air into the throated end of the tube, power mechanism for slowly opening and closing the gas valve, means for controlling the air valve including a solenoid and 20 adapted when the solenoid is energized substantially instantaneously to open the air valve and when said solenoid is deenergized substantially instantaneously to open the air valve, and current means for the solenoid controlled so that 25 the solenoid is energized as soon as the mechanism starts to open the gas valve and is de-

energized as soon as the mechanism starts to close said gas valve.

8. A burner of the character described comprising in combination a Venturi type injecting tube and provided with a burner head at its large 5 end and having a cross-wall at its throated end with slots therein for permitting air to flow into said throated end, a nozzle connected to receive gas under pressure and arranged to direct the gas so that it flows in jet form through the tube 10 to the burner head and entrains air into the throated end of the tube via certain slots for mixture therewith, a valve for controlling the supply of gas to the nozzle, a rotary register type valve fitting against said cross-wall and 15 adapted to control the flow of air into the throated end of the tube, mechanism for slowly opening and closing the gas valve, and automatic means including a solenoid and an armature between the solenoid and register type valve for substantially 20 instantaneously shifting said last mentioned valve into its open position as soon as the mechanism starts to open the gas valve and for substantially instantaneously shifting said register type valve into its closed position as soon as said 25 mechanism starts to close said gas valve.
